Robert B. Ogden
HIS ATTORNEY

UNITED STATES PATENT OFFICE.

FRED M. SLATER, OF EASTON, PENNSYLVANIA, ASSIGNOR TO INGERSOLL-RAND COMPANY, OF JERSEY CITY, NEW JERSEY, A CORPORATION OF NEW JERSEY.

WATER GUARD FOR ROCK DRILLS.

Application filed September 10, 1923. Serial No. 661,791.

To all whom it may concern:

Be it known that I, FRED M. SLATER, a citizen of the United States, and a resident of Easton, county of Northampton, and 5 State of Pennsylvania, have invented a certain Water Guard for Rock Drills, of which the following is a specification accompanied by drawings.

This invention relates to fluid actuated 10 rock drills of the hammer type, but more particularly to a front head water guard for stope drills.

In the operation of stope drills, much 15 annoyance and discomfort is occasioned to the operators by the muddy water from the drilled hole which runs down the drill steel and is thrown into the faces and upon the persons of the operators, by centrifugal force due to the rapid rotation of the front 20 head parts of the drill, and the primary object of the present invention is to overcome this annoyance in a simple manner.

Another object of the invention is to produce means for preventing muddy water 25 from being thrown upon the operator of a stope drill, which means are adapted to be cheaply manufactured and readily applied to the front head of the machine.

Further objects of the invention will 30 hereinafter appear and the invention is shown in one of its preferred forms in the accompanying drawings, in which—

Figure 1 is a vertical sectional view of the front end portion of a stope drill,

Figure 2 is a side elevation of a water 35 guard, and

Figure 3 is a view similar to Figure 2 with the water guard turned at right angles.

Referring to the drawings, A designates 40 the cylinder of a fluid actuated stope drill of the hammer type, in which the hammer piston B is adapted to reciprocate. Between the cylinder A and the front head C, is placed the usual front cylinder bushing D, in which is located the anvil block E. The chuck F in the front head C is adapted 45 to receive the drill steel G to which blows of impact of the hammer piston are transmitted through the anvil block E. Any 50 suitable means for rotating the drill steel G may be provided, but in this instance in-

dependent rotation means are indicated and the chuck F is formed with gear teeth H meshing with the pinion J on the driving shaft K, which is adapted to be rotated by 55 a suitable fluid actuated motor. The usual water tube L extends through the piston B and the anvil block E into the drill steel G for introducing water under pressure to the drill hole O, so that the cuttings may be 60 washed from the hole.

In order to prevent the slime formed by the mixture of cuttings and water in the hole O, which runs down the steel G, from 65 entering between the chuck F, and the front head C a shroud, preferably in the form of a plate P, may be secured to the chuck by means of a split ring Q, so that mud and water will flow over the sides of the 70 plate and not enter the rotating parts of the drill. In accordance with the present invention, a water guard in the form of a cap R is adapted to be attached to the front head C and is formed with a hole R' through 75

which the drill steel G extends. A series of slots S are formed in the sides of the cap R and are inclined downwardly, so that the stream of mud and water from the drilled hole which runs down the steel through the hole R, onto the rotating chuck, is thrown 80 against the sides of the cap, from which it flows downwardly through the inclined holes S along the sides of the drill. In this manner, the drill runner is protected and may operate the drill without the annoyance and discomfort of having mud and water constantly thrown in his face or upon 85 his person.

In this instance, the cap R is split as at T and lugs U are formed on the cap for receiving the bolt V on which is threaded the nut W, so that the cap may be readily removed from or attached to the front head, 90 as desired.

This cap is cheap to manufacture and has 95 proved to be an effective means for preventing mud and water from being thrown upon the drill operator.

I claim:

A rock drill comprising a cylinder, a 100 hammer piston within the cylinder, a front head for the cylinder, a chuck within the

front head adapted to receive a drill steel, said chuck being grooved at its end, a shroud in the form of a disk placed over the end of the chuck beneath said groove, a split ring in the groove holding the shroud in place, a removable water guard in the form of a split cap having rearwardly directed

apertures in its sides, located over the end of the front head, whereby the shroud within the cap may be removed by removing the cap.

In testimony whereof I have signed this specification.

FRED M. SLATER.
